UNITED STATES PATENT OFFICE.

FREDERICK W. KRONENBERG, OF PHILADELPHIA, PENNSYLVANIA.

STEAM BOILER.

Application filed June 19, 1925. Serial No. 38,268.

This invention relates to steam water boilers.

In steam water boiler constructions the front and rear headers are connected to each other by a plurality of tubes arranged in vertical series for exposure to the products of combustion and said headers also communicate with a steam drum from which water is supplied to the tubes through the rear header and to which the generated steam and remainder of the water is returned from said tubes by way of the front header, the tubes being inclined from their point of supply at the rear header to the points at which they discharge into the front header.

Under ordinary operating conditions sufficient water will be supplied to all of the tubes but the present day tendency is to force boilers so as to derive more power from them than they are actually supposed to produce. When being forced, however, the lower row of tubes, exposed directly to the fire in the combustion chamber, become very hot and practically all of the water therein is quickly converted to steam which rushes upwardly through the tubes to the front header and drum. In the absence of an adequate supply of water to these lower tubes which are exposed directly to the flame and which are subjected to intense heat, the tubes will become overheated, resulting in their bending, blistering or burning. At the same time, in ordinary boiler construction, it is difficult to insure the proper supply of water to the lower tubes due to the fact that the water supply enters the rear header at the top so that practically all of the water is sucked into the upper tubes, leaving insufficient supply for the lower tubes.

With these difficulties in view the present invention seeks to provide means for economically insuring an adequate supply of water to the lower tubes of the boiler, refinements of the construction consisting particularly in the adjustability and simplicity of such means.

With these and other objects in view, the invention consists in certain details of construction and combinations and arrangements of parts, all as will hereinafter be more fully described and the novel features

thereof particularly pointed out in the appended claims.

In the accompanying drawings,—

Figure 1 is a longitudinal sectional view of a boiler embodying the present improvements, some portions which are of no concern in the present case being shown more or less diagrammatical.

Fig. 2 is a transverse sectional view of a portion of the boiler, the steam drum being shown in elevation except for a small portion which is broken away to better illustrate the interior thereof;

Fig. 3 is a view taken on the section line 3—3 of Fig. 1;

Fig. 4 is a view taken on the section line 4—4 of Fig. 1;

Fig. 5 is a detail view illustrating one of the connections for supplying water to the lower tubes; and

Fig. 6 is a transverse section on the line 6—6 of Fig. 5.

While the present invention is applicable to various types of steam water boilers, the construction of boiler used for purposes of illustration in this instance comprises front and rear headers 10 and 11, which communicate with each other through a number of boiler tubes 12 preferably arranged in vertically disposed series and inclined forwardly from the rear header to the front.

The headers may, if desired, be formed in sections, as shown, and they each communicate with the steam drum 13 above them, the front header communicating therewith through pipes 14 and the rear header through nipples 15, there being one nipple for each header section. Below the rear header, and communicating therewith, is the mud drum 16.

With a construction as thus far described the supply of water to the lower tube of each series would be inadequate under the circumstances above described and to overcome this additional means are provided for supplying water to a point within the rear header directly opposite the rear ends of those tubes. These additional means consist of a tube or pipe 17 (termed a pipe to prevent confusion with the tubes proper) for each vertical series of tubes 12, the major portion of said pipes 17 being located within the drum and header to prevent the loss of

heat units as in the case of exterior, exposed pipes. In fact, those portions of pipes 17 not within the drum or header, are within the nipple and consequently surrounded by 5 water flowing through the latter so that no portion of said pipes are exposed to the exterior air.

The upper ends of pipes 17 are, of course, located below the working water level in 10 drum 13 and their lower ends project down within the header 11 to discharge water flowing therethrough at a point immediately opposite the desired tube, the lowermost tube in the present instance. As the pipes 17 actually extend almost to the bottom of the header, for a purpose which will later appear, they are preferably formed with one or more lateral openings or ports 18 a little above 15 their lower ends and in line with the lower tubes, the area of the opening or openings in each pipe being substantially equal to the cross section of the pipe. This also prevents the pipe directing the water away from the tubes or towards the mud drum 16.

20 In order to facilitate assembling of the pipes 17 and to permit adjustment of the orifices 18 therein with respect to the lower tubes, they are adjustably secured at their upper ends in the steam drum, the interior 25 of which is readily accessible through the man-holes 19. Preferably, the upper ends of said pipes project through a horizontally disposed plate 20 in the drum and each pipe is secured in said plate by a collar 21 held 30 on the upper extremity of the pipe above said plate by a set screw 22. This arrangement permits of the separate adjustment of each pipe to position the discharge orifices 35 therein in the plane of the lower tube, this independent adjustability of the individual 40 pipes being preferred to an arrangement for adjusting them collectively as would be the case if the plate 20 itself was adjustably supported in the drum.

45 Due to the creation of a partial vacuum in the lowermost tubes on account of the rapid conversion of the water to steam, water will be sucked down through pipes 17 from drum 13. These conditions tends to cause 50 the water to rush towards the tubes and will, therefore, set up vibration at the lower ends of the tubes. To hold said ends stationary, however, suitable means are provided for engaging and holding those portions of the 55 tubes which extend below the lowermost tubes. These means preferably consist of two oppositely disposed clamping members 23 whose intermediate portions are offset to receive between them the tube ends as shown 60 in Fig. 4. Near their ends the clamp members are provided with take-up means, such as the screw threaded bolts and nuts 24, whereby the tube may be securely clamped between the two members. At its opposite 65 ends, the clamp, thus formed, engages with

opposite walls of the header section so that the pipe held cannot vibrate or oscillate. In positioning the pipes in the header sections, the clamp is first inserted through the hole 25 in the header after which the pipe is inserted downwardly through the nipple 15 and its lower extremity placed in the clamp. The clamp is then taken up by means of the bolts and nuts 24 which are accessible through said holes 25.

70 It is not deemed necessary to give dimensions of any of the various parts but it will be understood that the relative diameters of pipes 17 and nipples 15 is such that the clearance between the two is sufficient to permit 75 the flow of water in quantities to take care of the upper rows of tubes 12.

What I claim is:

1. In a steam boiler, the combination with 80 the front and rear headers, tubes arranged in vertically disposed series between the headers, and a steam drum communicating with both of said headers, of means for insuring a supply of water from said drum to the lower portion of the rear header and the 85 lowermost tube supplied from that portion of the header, said means comprising a series of pipes extending from a point within the drum through the header to the bottom of the latter, the lower end of each pipe having lateral openings therein to discharge 90 water laterally of the header.

2. In a steam boiler, the combination with 95 the front and rear headers, tubes arranged in vertically disposed series between the headers, and a steam drum communicating with both of said headers, of means for insuring a supply of water from said drum to the lower portion of the rear header and the lowermost tubes supplied from that portion 100 of the header, said means comprising a series of pipes extending from a point within the drum through the header to the bottom of the latter, the lower ends of said pipes being held against vibrating and having lateral 105 openings therein, the size of the combined openings in each pipe being substantially 110 equal to the cross section of the pipe.

3. In a steam boiler, the combination with 115 the front and rear headers, tubes arranged in vertically disposed series between the headers, and a steam drum communicating with both of said headers, of supply connections for supplying water from the drum to the rear header at the point at which the lowermost tubes enter said header, said supply connections extending from within the header to the interior of the drum at which latter point they are adjustably secured.

4. In a steam boiler, the combination with 120 the front and rear headers, tubes arranged in vertically disposed series between the headers, and a steam drum communicating with both of said headers, of supply connections extending from within the header 125 130

- to a point within the drum, means for adjustably securing the supply connections in position whereby their lower ends may be adjusted in the header in line with the tubes to which it is desired to supply water through said connections. 5
5. In a steam boiler, the combination with the front and rear headers, tubes arranged in vertically disposed series between the headers, and a steam drum communicating with both of said headers, of supply connections extending from within the header to a point within the drum, means for adjustably securing the supply connections in 10 position whereby their lower ends may be adjusted in the header in line with the tubes to which it is desired to supply water through said connections, and means for holding the lower ends of said connections 15 against vibration. 20
6. In a steam boiler, the combination with the front and rear headers, tubes arranged in vertically disposed series between the headers, and a steam drum communicating with both of said headers, of a series of supply connections extending from a point within the rear header upwardly through said header into the drum, the lower ends 25 of said connections having discharge openings therein, and the said connections being separately adjustable vertically of the rear header. 30
7. In a steam boiler, the combination with the front and rear headers, tubes arranged in vertically disposed series between the headers, and a steam drum communicating with both of said headers, of a bar mounted in said drum and a supply connection for each series of tubes adjustably secured on said bar, said connection extending from said bar downwardly through the drum and rear header and having a lateral discharge opening near its lower end. 35
8. In a steam boiler, the combination with the front and rear headers, tubes arranged in vertically disposed series between the headers, and a steam drum communicating with both of said headers, of a bar mounted in said drum and a supply connection for each series of tubes on said bar, said connections extending from the bar downwardly through the drum and header and having discharge openings near their lower ends, 40 each of said connections being separately adjustable on the bar and a separate clamping member for the lower end of each connection to hold the latter against vibration. 45
9. In a steam boiler, the combination with the front and rear headers, tubes arranged in vertically disposed series between the headers, and a steam drum communicating with both of said headers, of a bar mounted in said drum and a supply connection for each series of tubes on said bar, said connections extending from the bar downwardly through the drum and header and having discharge openings near their lower ends, 50 each of said connections being separately adjustable on the bar and a separate clamping member for the lower end of each connection to hold the latter against vibration. 55
10. In a steam boiler, the combination with the front and rear headers, tubes arranged in vertically disposed series between the headers, and a steam drum communicating with both of said headers, of a bar mounted in said drum and a supply connection for each series of tubes on said bar, said connections extending from the bar downwardly through the drum and header and having discharge openings near their lower ends, 60 each of said connections being separately adjustable on the bar and a separate clamping member for the lower end of each connection to hold the latter against vibration. 65
11. In a steam boiler, the combination with the front and rear headers, tubes arranged in vertically disposed series between the headers, and a steam drum communicating with both of said headers, of a bar mounted in said drum and a supply connection for each series of tubes on said bar, said connections extending from the bar downwardly through the drum and header and having discharge openings near their lower ends, 70 each of said connections being separately adjustable on the bar and a separate clamping member for the lower end of each connection to hold the latter against vibration. 75
